UNITED STATES PATENT OFFICE

95,223

DESIGN FOR A DRESS

Johnnye Lee Caston, Chicago, Ill., assignor to
The Sterling Company, Chicago, Ill., a corporation of West Virginia

Application January 14, 1935, Serial No. 54,839

Term of patent 3½ years

To all whom it may concern:

Be it known that I, Johnnye Lee Caston, a citizen of the United States, residing at Chicago, in the county of Cook and State of Illinois, have invented a new, original, and ornamental Design for a Dress, of which the following is a specification, reference being had to the accompanying drawing, forming a part thereof.

Fig. 1 is a perspective front view of a dress embodying my design; and

Fig. 2 is a perspective view in contour of the rear of the dress shown in Fig. 1, it being understood that the material of the dress has the same pattern illustrated in Figure 1.

I claim:

The ornamental design for a dress as shown and described.

In witness whereof, I hereunto subscribe my name this 10th day of January, 1935, at Chicago, Illinois.

JOHNNYE LEE CASTON.
